UNITED STATES PATENT OFFICE

JOHN W. BELL, OF CHICAGO, ILLINOIS

DESIGN FOR A COFFEE DISPENSER

Application filed October 22, 1932. Serial No. 45,502. Term of patent 7 years.

To all whom it may concern:

Be it known that I, JOHN W. BELL, a citizen of the United States, residing at Chicago, in the county of Cook and State of Illinois, have invented a new, original, and ornamental Design for a Coffee Dispenser, of which the following is a specification, reference being had to the accompanying drawing, which is a perspective view of the article showing my new design.

The rear side of the design appears the same as the front side.

I claim:—

The ornamental design for a coffee dispenser, as shown and described.

In testimony whereof I affix my signature.

JOHN W. BELL.
